(57) **CLAIM**

The ornamental design for a cradle for an electronic device, substantially as shown and described.

DESCRIPTION

FIG. 1 is a perspective front view of a cradle for an electronic device in accordance with the present design; FIG. 2 is a perspective rear view of the cradle shown in FIG. 1;

FIG. 3 is a front view of the cradle shown in FIG. 1;

FIG. 4 is a rear view of the cradle shown in FIG. 1;

FIG. 5 is a right side view of the cradle shown in FIG. 1;

FIG. 6 is a left side view of the cradle shown in FIG. 1;

FIG. 7 is a bottom view of the cradle shown in FIG. 1; and,

FIG. 8 is a top view of the cradle shown in FIG. 1.

Features illustrated in phantom using dashed lines (broken lines) are shown for exemplary purposes only and form no part of the claimed design.
